UNITED STATES PATENT OFFICE.

CHRISTIAN GILSON, OF PITTSBURGH, PENNSYLVANIA, ASSIGNOR TO WESTINGHOUSE ELECTRIC AND MANUFACTURING COMPANY, A CORPORATION OF PENNSYLVANIA.

BLADING.

Application filed August 22, 1922. Serial No. 583,593.

To all whom it may concern:

Be it known that I, CHRISTIAN GILSON, a citizen of the United States, and a resident of Pittsburgh, in the county of Allegheny and State of Pennsylvania, have invented a new and useful Improvement in Blading, of which the following is a specification.

My invention relates to turbine blading, more particularly to blading which is relatively wide compared to its height, and it has for its object to provide apparatus of the character designated which shall have partition or deflector members secured between the blades for the purpose of deflecting and changing the direction of flow of the motive fluid and of bracing the blading assembly.

Apparatus embodying features of my invention is illustrated in the accompanying drawings, forming a part of this application, in which: Fig. 1 is a longitudinal sectional view of a turbine having blading with my improved deflecting and bracing structure applied thereto; Fig. 2 is a perspective view showing a plurality of blades with my deflector and bracing structure applied thereto; Fig. 3 is a fragmentary sectional view taken along the line III—III of Fig. 1; and Figs. 4 and 5 are detail views of one of the deflectors and bracing elements.

In my application, Serial No. 554,988, filed April 18, 1922, and assigned to the Westinghouse Electric and Manufacturing Company, I show exhaust blading of the wide type, adapted to receive steam flowing in an axial direction and to discharge it peripherally, in which the blades are made in sections in order to facilitate manufacture. My present invention relates to deflector and bracing structure which is especially adapted for use in connection with sectionalized blading of this type.

Referring now to the drawings for a more detailed description of my invention, I show a turbine comprising a rotor 10, supported by the bearings 11 of the cylinder or casing 12, the rotor 10 and the cylinder or casing 12 carrying suitable energy-abstracting elements followed by a last stage at 13, including a row of guide blades 14 and a row of wide blades 15 adapted to receive axially-flowing steam and to discharge the latter radially or peripherally.

The wide blades 15 include inner approxi-

mately radial or plane portions 16 and outer curved or spoon-outline portions 17, the latter portions serving to expand and to discharge steam at small angles peripherally. The blades 15 are preferably composed of a plurality of sections 18 in order to facilitate manufacture, as set forth in my application aforesaid.

It is desirable to provide, in connection with wide blades of the type referred to, means to assist in changing the direction of flow of steam from an axial to a radial direction as well as to brace the blade structure. Accordingly, I have devised deflector and bracing members 20, each of which comprises a lower curved deflecting portion 21 and an outer partition member 22. Each of the deflecting and bracing members 20 is tapered so as to fit the tapering spaces between the blades, and the partition members are bordered at the sides by flanges 23 adapted to contact with the plane portions 16 at the rear of the sections 18, and the deflecting and bracing members are secured to the blade sections in any suitable manner, as by the rivets 24 or by spot-welding.

The deflecting and bracing members 20 are connected to the blade sections 18 in the following manner: After the first annulus of sections 18, adjacent to the guide blades 14, is assembled with respect to the rotor, the corresponding deflector and bracing members 20 are placed between the sections at the rear sides thereof with the outer ends of the deflector and bracing members adjacent to the curved or spoon-outline portions 17, and then the rivets 24 are inserted in the openings provided therefor in the blade sections and in the flanges 23 so that each rivet holds a blade section between the flanges of adjacent deflector and bracing members, or the flanges are shot-welded to the blade sections. The succeeding annuli of blade sections and corresponding deflector and bracing members are assembled in the same manner.

Upon reference to Figs. 1 and 2, it will be seen that the deflector and bracing members 20 for the blade sections 18 are successively longer from the inlet side of the wide blades 15 in order that the curved portions 21 thereof may successively divide the annulus of steam flowing in an axial direction between the blades into a plurality of portions and to change the direction of flow of each

of the latter portions toward a radial direction.

The partition and bracing portions 22 of the deflector and bracing members 20 co-operate with the blade sections to define radial channels 25 through which steam is guided for action upon the outer curved or spoon-outline portions 17; and, as the members 22 are placed between and secured 10 to the respective blade sections, the latter are firmly braced against vibration.

From the foregoing, it will be seen that I have devised combined deflector and bracing means for wide turbine blades which 15 renders it possible to provide wide blading of the sectionalized type in which vibration is practically negligible and which handles the steam with little, if any shock, in changing the direction of flow thereof.

20 While I have shown my invention in but one form, it will be obvious to those skilled in the art that it is not so limited, but is susceptible of various other changes and modifications, without departing from the spirit 25 thereof, and I desire, therefore, that only such limitations shall be placed thereupon as are imposed by the prior art or as are specifically set forth in the appended claims.

What I claim is:

30 1. In a turbine, a row of blades, each of which comprises a plurality of sections, and bracing means secured along the rear edges of the sections.

35 2. In a turbine, a row of blades, each of which comprises a plurality of radial sections, and radially-arranged bracing means secured to the rear edges of the sections.

40 3. In a turbine, a row of blades, each of which comprises a plurality of radial sections, radially-arranged bracing means secured to the rear edges of the sections, and deflector means carried by the inner ends of the bracing means.

45 4. In a turbine, a row of blades adapted to receive steam flowing in an axial direction and to discharge it peripherally and having outer curved, energy-absorbing portions, radially-arranged bracing means secured between the blades, and deflectors carried by the bracing means and arranged successively lower from the inlet sides of the blades in order to successively divide the steam into a plurality of portions and to change the direction of flow of each portion 50 from an axial toward a radial direction.

55 5. In a turbine, a row of blades adapted to receive steam axially and to discharge it peripherally, each of said blades being composed of a plurality of sections placed side by side, and deflecting and bracing members secured to like sections of adjacent blades to brace the sections and to guide and deflect steam toward the blade tips.

60 6. In a turbine, a row of blades adapted to

receive steam axially and to discharge it 65 peripherally, each of said blades being made in sections, and members of different lengths secured at the rear sides of corresponding sections and having at their lower ends curved deflector members to change the direction of flow of steam from an axial toward a radial direction.

7. In a turbine, a row of sectionalized, tip-discharging blades and deflectors for successively deflecting portions of the steam toward the tips and maintaining the portions 75 separate.

8. In a turbine, a row of blades adapted to receive axially flowing steam and to discharge it peripherally, each of said blades 80 comprising a plurality of radial sections, and radially-arranged partition members of different lengths respectively secured to corresponding sections of the blades and having curved steam deflector portions at their lower 85 ends to change the direction of flow from an axial toward a radial direction.

9. In a turbine, a row of blades and a plurality of deflector members of different lengths secured to the blades and having inner curved deflector portions and straight 90 portions extending toward the blade tips.

10. In a turbine, a row of blades adapted to receive steam axially and to discharge it 95 peripherally, means for successively dividing the in-flowing annulus of steam into a plurality of annuli, means for changing the direction of flow of each of the latter from an axial toward a radial direction, and supporting means secured to the last-named 100 means, extending in a radial direction, and secured to the blades for bracing the latter and serving as guides to insure the flow of steam in a radial direction.

11. In a turbine, a row of blades adapted 105 to receive steam axially and to discharge it peripherally, a plurality of radial partitions secured to and between adjacent blades, and steam deflectors carried by the partitions.

12. In a turbine, a row of blades adapted to receive steam at one side and to discharge it 110 peripherally, and having outer curved energy-absorbing portions, spaced partition members of different lengths secured to and 115 between the blades to brace the latter and to constitute a plurality of radial passages between adjacent blades increasing in length from the inlet to the rear sides of the blades, and means carried by the inner ends of the partitions for deflecting portions of the 120 steam and for changing direction of flow thereof from an axial toward a radial direction.

In testimony whereof, I have hereunto 125 subscribed my name this 15th day of August, 1922.

CHRISTIAN GILSON.
